UNITED STATES PATENT OFFICE.

MICHAEL JOSEPH GALVIN, OF NORTH BAY, ONTARIO, CANADA.

NOZZLE.

1,157,861.

Specification of Letters Patent.

Patented Oct. 26, 1915.

Application filed November 6, 1914. Serial No. 870,601.

To all whom it may concern:

Be it known that I, MICHAEL JOSEPH GALVIN, of the town of North Bay, in the district of Nipissing, in the Province of Ontario, Canada, have invented certain new and useful Improvements in Nozzles, of which the following is the specification.

My invention relates to improvements in nozzles and the object of the invention is to devise means for automatically mixing a stream of chemical solution with a stream of water passing under pressure from a hydrant through the nozzle and it consists essentially of a main nozzle conical in form, a water nozzle extending through the main nozzle, and discharging into the interior of the main nozzle in proximity to the main nozzle outlet, a chemical solution supply nozzle also passing through the main nozzle and discharging into the main nozzle in close proximity to the discharge outlet of the water supply nozzle and on that side of the discharge outlet of the water supply nozzle remote from the discharge outlet of the main nozzle as herein-after more particularly explained by the following specification.

Figure 1, is a sectional perspective view of my device showing the water supply and chemical solution supply nozzles in full. Fig. 2, is a longitudinal section through my device. Fig. 3, is an enlarged cross section on line $x-y$ Fig. 2.

In the drawings like characters of reference indicate corresponding parts in each figure.

1 is the main nozzle comprising a hollow conical body having a nozzle outlet 2 at the apex of the cone. 3 is a hose or other flexible duct connection leading to the hydrant or water supply.

4 is a union connecting the hose 3 to the portion 5 of the main nozzle 1.

6 is a tapered nozzle fitting into a correspondingly tapered orifice 7, the discharge outlet of the nozzle 6 being in close proximity to the discharge outlet 2 of the main nozzle.

9 is a supplemental hose connection leading to a suitable tank containing chemical solution, the tank not being shown.

10 is a union connecting the hose 9 to the portion 5.

11 is a tapered nozzle fitting at its upper end into a correspondingly tapered hole 13 formed in the portion 5, the lower end 55 of the nozzle 11 being cut away at 14 so as to fit closely up to the nozzle 6 and form a lunar shaped opening 15. By this means the outlet end of the nozzle 11 is brought very close to the outlet of the nozzle 6. 60

Having described the principal parts involved in my invention I will briefly describe the operation of the same. When the hose connections 3 and 9 have been connected to their respective sources of supply the water fed by the hydrant is turned on and the water passes through the hose connection 3, through the nozzle 6 and through the outlet 2 of the main nozzle 1. The rush of water through the extreme 70 point of the main nozzle creates a vacuum in the main nozzle and in the chemical solution supply nozzle 11. This vacuum serves to draw the solution from the supply tank through the hose 9 and nozzle 11 75 so as to mix with the stream of water passing between the outlet of the nozzle 6 and the outlet of the nozzle 1.

It will be readily understood that such a device will be found applicable to many 80 purposes where it is desired to mix a chemical solution with a stream of water under pressure such as in a hand fire extinguisher or in many forms of spray nozzles used for fumigating or treating of fruit trees and 85 the like.

Although only one nozzle 11 has been shown through which the chemical solution is drawn it will, of course, be understood that a plurality of nozzles could be employed, each of such nozzles being connected to a separate receptacle, each receptacle containing a different solution. When these solutions are drawn through the chemical supply nozzles into the main nozzle they 90 may combine and form a gas which would add to the pressure of the stream through the main nozzle. This will be particularly valuable in cases where my device is employed as a fire extinguisher. 95 100

What I claim as my invention is.

A device of the class described comprising a primary nozzle, a secondary nozzle having a diagonally cutaway lower portion, said portion located adjacent the lower end of said primary nozzle, a casing for inclosing said nozzles comprising a hollow coni-

cal body having an outlet opening at its apex, and closure means for the base of said conical body supporting said nozzles.

MICHAEL JOSEPH GALVIN.
